(57) **CLAIM**

The ornamental design for a stool, as shown and described.

DESCRIPTION

FIG. 1 is a top, front, perspective view of a stool showing a first embodiment of our new design;
FIG. 2 is a left side elevation view thereof;
FIG. 3 is a right side elevation view thereof;
FIG. 4 is a front elevation view thereof;
FIG. 5 is a rear elevation view thereof;
FIG. 6 is a top plan view thereof;
FIG. 7 is a bottom plan view thereof;
FIG. 8 is a top, front, perspective view showing a second embodiment thereof;
FIG. 9 is a left side elevation view of FIG. 8;

FIG. 10 is a right side elevation view of FIG. 8;
FIG. 11 is a front elevation view of FIG. 8;
FIG. 12 is a rear elevation view of FIG. 8;
FIG. 13 is a top plan view of FIG. 8;
FIG. 14 is a bottom plan view of FIG. 8;
FIG. 15 is a top, front, perspective view showing a third embodiment thereof;
FIG. 16 is a left side elevation view of FIG. 15;
FIG. 17 is a right side elevation view of FIG. 15;
FIG. 18 is a front elevation view of FIG. 15;
FIG. 19 is a rear elevation view of FIG. 15;
FIG. 20 is a top plan view of FIG. 15;
FIG. 21 is a bottom plan view of FIG. 15;
FIG. 22 is a top, front, perspective view showing a fourth embodiment thereof;
FIG. 23 is a left side elevation view of FIG. 22;
FIG. 24 is a right side elevation view of FIG. 22;
FIG. 25 is a front elevation view of FIG. 22;
FIG. 26 is a rear elevation view of FIG. 22;
FIG. 27 is a top plan view of FIG. 22;
FIG. 28 is a bottom plan view of FIG. 22;

FIG. 29 is a top, front, perspective view showing a fifth embodiment thereof;
FIG. 30 is a left side elevation view of FIG. 29;
FIG. 31 is a right side elevation view of FIG. 29;
FIG. 32 is a front elevation view of FIG. 29;
FIG. 33 is a rear elevation view of FIG. 29;
FIG. 34 is a top plan view of FIG. 29;
FIG. 35 is a bottom plan view of FIG. 29;
FIG. 36 is a top, front, perspective view showing a sixth embodiment thereof;
FIG. 37 is a left side elevation view of FIG. 36;
FIG. 38 is a right side elevation view of FIG. 36;
FIG. 39 is a front elevation view of FIG. 36;
FIG. 40 is a rear elevation view of FIG. 36;
FIG. 41 is a top plan view of FIG. 36; and,
FIG. 42 is a bottom plan view of FIG. 36.

The dashed broken lines of the figures represent portions of the stool that form no part of the claimed design. The dash-dot broken lines define boundaries of the claimed design, and form no part of the claimed design.
